By attorney.

UNITED STATES PATENT OFFICE.

ALFRED V. E. LUND, OF PHILADELPHIA, PENNSYLVANIA, ASSIGNOR OF ONE-HALF
TO WILLIAM J. STRANDWITZ, OF HADDONFIELD, NEW JERSEY.

MEMORANDUM-CARD.

1,381,925.

Specification of Letters Patent. Patented June 21, 1921.

Application filed February 27, 1920. Serial No. 361,766.

To all whom it may concern:

Be it known that I, ALFRED V. E. LUND, a citizen of the United States, and resident of Philadelphia, county of Philadelphia, State 5 of Pennsylvania, have invented an Improvement in Memorandum-Cards, of which the following is a specification.

My invention has for its object the making of a satisfactory vest pocket memorandum card which is adapted to fit into and 10 clamp upon the front portion of the pocket cloth, whereby it may be accessible at all times without danger of becoming lost, and furthermore, so constructed that it does not 15 offer interference to the use of the pocket for pencils or similar articles which are usually carried in the vest pocket.

My object is further to so construct the memorandum card that it is provided with a 20 pivoted leaf which, when turned in alignment with the card proper, the two parts present oppositely arranged faces upon which the writing may be made, said faces preferably having a dulled surface suitable 25 for receiving and retaining the pencil marks; the construction being further such that when the pivoted leaf is turned into adjusted relation with the card proper, the 30 written matter is fully protected between the two leaves and the pivoted leaf is moreover shielded under the clamping device and so that its upper end is clamped between the 35 card proper and the cloth of the pocket, and thereby held against displacement. In practice, I prefer to form the memorandum card device of celluloid with the outer faces 40 polished, while the inner adjacent faces are of dead finish upon which the writing may be made, the polished surface offering no resistance for the insertion of papers or other 45 articles within the pocket while the card is also positioned therein.

My invention also consists of improvements hereinafter described whereby the 50 above objects and results are attained, said improvements comprising certain organization and combination of parts which are fully described hereinafter and more particularly defined in the claims.

Referring to the drawing: Figure 1 is a 55 front view of my improved memorandum card in position for insertion into the pocket; Fig. 2 is a similar view with the pivoted leaf turned sidewise to some extent to indicate its adjustability over the main card portion;

Fig. 3 is a perspective view of the memorandum card in its closed position corresponding to Fig. 1; Fig. 4 is a rear elevation of the memorandum card with the pivoted leaf turned down into alignment with the main card portion to expose the deadened surface upon which the writing may be placed; and Fig. 5 is a vertical section through a vest pocket and showing my improved memorandum card applied thereto. 60

The main memorandum card is indicated at 2 and is preferably rectangular in form with its greatest length vertically arranged to fit the depth of the pocket; and the upper end of the said card, at its middle portion 4, is 65 provided with an overturned clamping tab 3 which extends down somewhat in front of the face of the card 2 and at a slight distance removed therefrom, so as to provide a space immediately below the upper curved 70 portion 4, to receive the upper edge 8 of the pocket 7 of the garment, (Fig. 5). The tab 3 is preferably slightly curved outward at its lower part, so that when the card is inserted into the pocket, the tab passes to the 75 outside thereof and provides a clamping connection upon the part 8 of the pocket to retain the memorandum card from dropping out of the pocket when leaning over or when subjected to disturbing influences. The upper curved or projecting neck portion 4, in 80 addition to the tab 3, provides means for removing the memorandum card from the pocket when it is desired to have access to it for purposes of making or reading memo- 85 randa. 90

In addition to the main card 2, there is 95 preferably provided a pivoted leaf 5 of the same general rectangular shape as the card 2 and the same pivoted at the bottom, as at 6, by a suitable eyelet or other means, so that the said leaf may be turned up under the tab 3 to fit exactly over the card 2 and shield the writing face thereof (as shown in Figs. 1, 3 and 5), when it is adapted to be placed 100 in the pocket, or which may be turned vertically outward (as indicated in Fig. 4), when it is desired to read the memorandum upon the card 2, (Fig. 2), or to read the memorandum recorded upon the pivoted leaf, (Fig. 4). When this open adjustment is made, it is also for the purpose of adding additional memoranda, if so desired. 105

In practice, the parts 2 and 5 are made of celluloid with the tab bent over while warm, 110

and set when cooled to constitute a spring clamp for holding the memorandum card in position in the pocket. In practice, the opposing surfaces of the two cards 2 and 5, which receive the memorandum, have deadened surfaces, whereas the opposite sides or those exposed are made with polished surfaces, though I do not necessarily confine myself to this latter requirement.

10 While my improved memorandum card is preferably formed of celluloid, because of its cheapness, cleanliness, flexibility and adaptability for receiving pencil inscriptions, I do not restrict myself thereto, as the 15 card structure may be made of metal, if so desired. Furthermore, the main card 2 may be formed of metal or celluloid, as desired, while the front leaf 5 may be made of hard calendered cardboard, if so desired. Furthermore, it will be understood that the 20 pivoted leaf 5 may be omitted where a lesser memorandum capacity is required for the card, and in that event, the card 2 with its deadened surface adjacent to the tab 3 may 25 alone be employed in connection with the vest pocket.

It will now be apparent that I have devised a novel and useful construction which embodies the features of advantage enumerated as desirable, and while I have in the 30 present instance shown and described the preferred embodiment thereof which has been found in practice to give satisfactory and reliable results, it is to be understood 35 that I do not restrict myself to the details, as the same are susceptible of modification in various particulars without departing from the spirit or scope of the invention.

Having now described my invention, what

I claim as new and desire to secure by Letters Patent, is:—

1. A vest pocket memorandum card device, comprising a card of general rectangular shape having a finish upon one side suitable to receive writing, and further provided at its upper end with a clamping tab facing the finished side aforesaid of the card, said tab constituting an integral extension of the card material at the top edge thereof and positioned by a bent over neck portion, 50 whereby the tab has a spring clamping action adapted to clamp the card to the vest pocket.

2. The invention according to claim 1, further characterized by having a hinged 55 leaf of similar general rectangular shape, one face thereof finished to receive writing, and said leaf hinged to the card adjacent its lower portion, whereby the leaf may be adjusted in a plane parallel to the surface 60 of the card and normally lie upon the face of the card with its edge most distant from the hinge engaged back of the tab and between it and the card.

3. As an article of manufacture, a vest 65 pocket memorandum device comprising a substantially rectangular shaped card of celluloid having a spring clamping tab also of celluloid integral with the upper edge of the card and extended down approximately 70 to and facing the writing surface of the card, the tab and card surface being separated sufficiently to receive and engage the cloth edge of a pocket.

In testimony of which invention, I here- 75 unto set my hand.

ALFRED V. E. LUND.
